PORTABLE RECEPTACLE

Harry Isaacson, Brooklyn, N. Y., assignor to Jacob Schoenfeld, New York, N. Y.

Application July 12, 1933. Serial No. 680,002

4 Claims. (Cl. 150—28)

This invention relates to portable receptacles and has among its objects the provision of improved means for securing a section or cover to a bag, and the further provision of an improved reversible cover for a bag.

A further object of the invention is to furnish a portable receptacle of the character described having few and simple parts and which is inexpensive to manufacture, neat in appearance, durable, reliable, and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation of a device embodying the invention.

Fig. 2 is a view in end elevation thereof.

Fig. 3 is a view in rear elevation thereof.

Figs. 4 and 6 are enlarged horizontal sectional views taken on lines 4—4 and 6—6 respectively of Fig. 3.

Fig. 5 is a vertical sectional view taken on line 5—5 of Fig. 1.

Fig. 7 is an enlarged view of the removed reversible cover.

Fig. 8 is a vertical sectional view taken on line 8—8 of Fig. 7.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a portable receptacle, such as a ladies' handbag embodying the invention. The same may have a conventional bag portion 11 which for purposes of illustration, may include side walls 12 and 13, of which the latter may consist of two plies of material 14 and 15. The ply or lining 15 and the wall 12 may be interengaged by gussets 16, 17, secured by stitching 18, while the plies 14 and

15 may be cemented or stitched together, except that a marginal portion 19 of the ply 15 may be separated from the companion ply for a purpose that will be described hereinafter. The bag 11 may desirably be open at 20 at its upper end, and at one side thereof adjacent to its lower end a flap 21 may be secured as at 22, said flap having a headed stud 23 on the inside face thereof.

Secured marginally along the wall 13 is a reinforcing and/or connecting means such as sections or elements which may be combined in a one piece channel member 24 of U-shaped form, having a lower section 25 extending along the bottom of the bag and side arms 26 extending along end edges of said bag. The cross section of the channel may be uniform throughout and may have a back 27 and flanges 28 and 29 lying in substantially parallel planes and of which the latter may have a greater width than the former. In this way the arms 26 are amply stiff, and, if required, the flanges 29 may be made of any required area, consistent with lightness. Said flanges 29 are received in the marginal spaces between edge portions 19 and 19a of the members 15 and 14 respectively, which edge portions may be secured continuously to said flanges as by cement and reinforcingly connected thereto at spaced points as by rivets 30 that pass through members 14 and 29. The channel member 26 may have its upper ends 31 terminating at the mouth 20 of the handbag.

Coacting with the bag 11 is a cover 32 removably or adjustably connectible thereto as for the purpose of reversibility. Thus the cover may have sheet of material 33 that may consist of one or more plies and which may have a color, finish, or character on a face 34 thereof different from that on the opposite face 35 thereof. Said sheet 33 may have a section 36 provided with reinforcing and/or securing means which may be in the nature of sections or elements that may be embodied in a U-shaped member 37. Thus the latter may have a lower section 38 at an end of the cover and side arms or sections 39 extending along the edges of the cover section 36. While the member 37 may be variously secured to the sheet of material 33, it is preferably formed in the nature of a bead that is continuously clamped to marginal portions of the cover section 36. The other section 36a of the cover may be free of the member 37, and may have an eyelet 40 secured therein for reversible releasable engagement with the stud 23. It will thus be seen that the cover may be of uniform constructional appearance on both faces thereof.

In assembly, the cover section 36 is applied to the bag 11 with the beaded reinforcement 37 slidably inserted into the corresponding channel member 29 so that the U-shaped formations of 5 both are similarly arranged. A simple movement along a plane parallel to that of the wall 13 suffices for such interengagement. The relation of the member 37 to the channel may further be such that the flange 28 substantially 10 overlies and conceals the same, preferably without contacting the fabric 33, and with the upper ends 41 of the member 37 terminating at the upper ends 31 of the channel. Contact of the flange 29 with the cover is prevented by the cushioning sheet of fabric 15, this being important 15 since the cover is subjected in ordinary use to considerable pressure toward said flange. The cover section 36a is then folded at 42 over the opening 20 of the bag and downward along 20 the wall 12 for connection with the flap 21.

The cover section 36 may be releasably secured in any suitable manner, to the channel 24, preferably by snap action brought about coincidentally with the insertion into the channel. Thus the 25 back 27 of the latter in relative proximity to the upper ends thereof may have openings 43 struck therein, and the adjacent portions of the bead member may have projections 44 extending therefrom, constructed and arranged to engage in the 30 openings 43 in different positions of the cover. A small degree of resilience of the arms 39 or 26, or both, relative to each other, will impart the desired releasability to the fastening means 43, 44.

35 It will thus be perceived that the arms 39 may be reenforcingly interconnected in proximity to their ends 41, although this is not essential, especially as the fabric 33 may have sufficient strength or stiffness if additional reinforcement 40 be desired.

In any case, in connecting the cover to the bag 11, the bead member 37 avoids any wear of the fabric 33 against the channel 24.

45 I have found that the advantages of the invention are best understood when the same is embodied in a flexible type handbag, such as one that is free of any frame members except the members 25 and 37. However, the invention is also applicable to bags of other types.

50 It will be noted that the cover provides an additional compartment 45 as for papers and cards, and which compartment is opened and closed by the cover section 36a at the same time as the bag.

55 By this invention, the handbag is calculated to have minimum wear and long life. The securing means for the cover is expeditious in use, neat in appearance, functions as a continuous stiffener while maintaining the pliability of the 60 handbag. The handbag can be rapidly converted from one for everyday use to one for evening wear. It will be understood that the outside faces of the flap 21 and the wall 12 may be the same in 65 appearance as that of one face of the cover. If the opposite face of the cover be on the outside, the flap will form a pleasing effect or contrast with the cover.

It will be appreciated that various changes and

modifications may be made in the device as shown in the drawing, and that the same is submitted in an illustrative and not in a limiting sense, the scope of the invention being defined in the following claims.

80 I claim:

1. A handbag including a bag, a U-shaped channel member having inner and outer flanges, the inner flanges being secured to a side wall of the bag, a reversible cover for the bag, said cover having a flexible body and a marginal U-shaped reinforcement therefor, said reinforcement being removably slidable into and out of the channel member, said outer flanges having longitudinal edges coincident with the edges of said reinforcement and spaced from the flexible body, and a sheet of pliable material connected to said bag and overlying said inner flanges for maintaining the same out of contact with said flexible body portion against pressure exerted on the latter. 95

2. A handbag including a bag having a side wall, a U-shaped channel member having a back and inner and outer flanges, the inner flange being connected to the side wall exteriorly of the bag, a reversible cover for the bag, said cover 100 having a flexible body and a marginal U-shaped reinforcement member removably slidable into the channel member for connecting the cover to the bag, the outer flange having its longitudinal free edge coincident with the corresponding 105 edge of the reinforcement member and spaced from said body, and a sheet of fabric continuously connected to the exterior face of said bag wall and to the inner flanges and overlying the latter, and said sheet of fabric terminating in spaced relation to the back of the channel member.

3. A handbag including a bag having a side wall, a U-shaped channel member having a back and inner and outer flanges, the inner flange being connected to the side wall exteriorly of the 115 bag, a reversible cover for the bag, said cover having a flexible body and a marginal U-shaped reinforcement member removably slidable into the channel member for connecting the cover to the bag, said U-shaped members being resilient so as to cause corresponding arms of the members to tend to move in opposite directions 120 for resilient interengagement of the members, the outer flange having its longitudinal free edge coincident with the corresponding edge of the 125 reinforcement member and spaced from said body, and a sheet of fabric continuously connected to the exterior face of said bag wall and to the inner flanges and overlying the latter.

4. A handbag including a bag, a reversible 130 cover therefor, said bag having a side wall, a U-shaped channel member having inner and outer flanges, said cover having portions removably received in said channel member, a lining for the outer surface of said wall of less thickness 135 than the latter, the lining and wall being interconnected along the channel member, the latter extending along the edges of the side wall and having the inner flange thereof received between edge portions of the said wall and lining and secured to the same. 140

HARRY ISAACSON.
